(57) **CLAIM**

The ornamental design for a multi-purpose travel bag, as shown and described.

DESCRIPTION

FIG. 1 is a top, front, left side perspective view of a multi-purpose travel bag showing our new design;

FIG. 2 is a front side elevation view of the multi-purpose travel bag as shown in FIG. 1;

FIG. 3 is a rear side elevation view of the multi-purpose travel bag as shown in FIG. 1;

FIG. 4 is a right side elevation view of the multi-purpose travel bag as shown in FIG. 1;

FIG. 5 is a left side elevation view of the multi-purpose travel bag as shown in FIG. 1;

FIG. 6 is a top plan view of the multi-purpose travel bag as shown in FIG. 1;

FIG. 7 is a bottom plan view of the multi-purpose travel bag as shown in FIG. 1;

FIG. 8 is a top, front, left side perspective view of the multi-purpose travel bag shown in FIG. 1, shown with the egress panel in an opened configuration and with the handle feature extended;

FIG. 9 is a top, front, left side perspective view of the multi-purpose travel bag shown in FIG. 1, shown in an extended configuration;

FIG. 10 is a front side elevation view of the multi-purpose travel bag as shown in FIG. 9;

FIG. 11 is a rear side elevation view of the multi-purpose travel bag as shown in FIG. 9;

FIG. 12 is a right side elevation view of the multi-purpose travel bag as shown in FIG. 9;

FIG. 13 is a left side elevation view of the multi-purpose travel bag as shown in FIG. 9;

(Continued)

FIG. 14 is a top plan view of the multi-purpose travel bag as shown in FIG. 9;

FIG. 15 is a bottom plan view of the multi-purpose travel bag as shown in FIG. 9; and,

FIG. 16 is a top, front, left side perspective view of the multi-purpose travel bag shown in FIG. 9, shown with the egress panel in an opened configuration, with a collapsible chassis between the base and the top receptacle portion in an extended position, and with the handle feature extended. In the drawings, the short dash broken lines are for the purpose of illustrating environment and portions of the multipurpose travel bag that form no part of the claimed design. The longer dash broken lines are for the purpose of illustrating certain stitching that also do not form part of the claimed design. The broken lines depicting zipper elements form no part of the claimed design.

1 Claim, 14 Drawing Sheets
